[57] CLAIM

The ornamental design for a miniaturized dental X-ray film duplicator, substantially as shown.

DESCRIPTION

FIG. 1 is a front perspective view of a miniaturized dental X-ray film duplicator, showing my new design; FIG. 2 is a front elevational view thereof; FIG. 3 is a left side elevational view thereof; FIG. 4 is a right side elevational view thereof. FIG. 5 is a top plan view thereof, taken from the top of FIG. 2; FIG. 6 is a bottom plan view thereof, taken from the bottom of FIG. 2; and FIG. 7 is a rear elevational view thereof.
